UNITED STATES PATENT OFFICE.

JOHN E. OSMER, OF BOONE, IOWA, ASSIGNOR TO THE FISHER GOVERNOR COMPANY, OF MARSHALLTOWN, IOWA, A CORPORATION.

FLUID-REGULATOR.

1,110,294.

Specification of Letters Patent.

Patented Sept. 8, 1914.

Application filed January 25, 1913. Serial No. 744,239.

To all whom it may concern:

Be it known that I, JOHN E. OSMER, a citizen of the United States, residing at Boone, Iowa, have invented certain new and useful Improvements in Fluid-Regulators, of which the following is a specification.

This invention relates to improvements in fluid regulators.

The main objects of this invention are: First, to provide an improved regulator mechanism adapted for use either as a pressure or vacuum regulator, a reducing valve, or a pump governor. Second, to provide an improved fluid regulator mechanism in which the valve and valve cage can be readily removed for repair without removing the mechanism from the line in which it is installed. Third, to provide an improved regulator mechanism in which the parts are simple and economical to produce and very easily assembled or disassembled should occasion require.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Figure I is a detail side elevation of a structure embodying the features of my invention. Fig. II is a detail plan view of the structure appearing in Fig. I. Fig. III is a detail vertical section on a line corresponding to line 3—3 of Fig. I. Fig. IV is a detail vertical section on a line corresponding to line 4—4 of Fig. II. Fig. V is a horizontal section on a line corresponding to line 5—5 of Fig. III.

In the drawings, similar reference characters refer to similar parts throughout the several views, and the sectional views are taken looking in the direction of the little arrows at the ends of the section lines.

Referring to the drawing, the valve casing or body 1 is provided with internally threaded nipples 2 into which the line pipes 3 and 4 are threaded. In the structure illustrated, the pipe 3 is the inlet, and the pipe 4, the discharge. It is obvious that the body

might be provided with suitable coupling flanges in lieu of the coupling nipples 2 and such couplings are preferred in the larger sizes. The body in the structure illustrated, is open at both ends and has a cylindrical bore adapted to receive the cylindrical valve cage 5 having spaced valve seat holders 6 therein adapted to receive the valve seats 7.

The casing heads 8 are removably secured by means of the screws 9. These removable heads 8 fit against the flat ends of the casing. The casing is provided with an annular passage 19 surrounding the cylindrical valve cage 5, the cage being provided with opposed ports 11 communicating with this passage, the ports opening between the valves 12. These valves are of the disk type and beveled to coact with the valve seats 7 mounted on the valve seat holders 6. The valves 12 are mounted on a valve stem 13 common to both, the stem being arranged through suitable packing glands designated generally by the numerals 14, 14. The valves are provided with a spacing sleeve 15. The valves are retained by the lock nuts 16. To assist the stem in guiding the valves, the valves are provided with wings 17 which project through and are in sliding engagement with the valve seat holders 6. The valves are thus very effectively supported and guided, which is a feature of great advantage where the regulator is used on high pressures.

The valve casing 1 is provided with a passage 18 communicating with the pipe 4, while the heads are provided with passages 19 connecting the passage 18 with the ends of the cylindrical valve cage. The valves 12 are slightly out of balance,—that is, one is of a somewhat greater area than the other so that the pressure tends to open the same. Packing disks 20 are fitted within the ends of the valve cage as illustrated, to assist in forming a tight joint for the heads.

The regulating diaphragm chamber casing or body 21 is mounted on a bracket 22 on the side of the body 1 by means of the screw 23. The diaphragm 25 is supported within the diaphragm chamber by clamping its edges between the sections forming the diaphragm chamber casing,—see Fig. IV.

The lower section 26 of the diaphragm chamber casing is provided with a cylinder extension 27 in which the regulating spring 28 is arranged. This spring 28 is arranged

about the stem 29 of the diaphragm 25. The stem projects through the spring adjusting member 30 by which the spring is supported. The member 30 is provided with a lock nut 31. The stem is connected by the lever 32 to the stem 13 of the fluid valves. The lever 32 is fulcrumed on the hanger 33 carried by the bracket 22. The pipe 34 connects the regulating or diaphragm chamber with the fluid tank, radiator, or the like.

To adapt the structure to high pressures, a pipe 35 is connected to the diaphragm chamber below the diaphragm. This has the effect of reducing the area of the pressure on the diaphragm as the diaphragm is provided with a plunger 36 which projects into the cylinder extension 27 of the diaphragm chamber, the plunger being provided with a suitable packing. The pipe 35 is provided with a valve 37 so that it may be cut off when desired. This pipe 35 is connected to the pipe 34 or to the same source of fluid supply. The cylinder 27 is provided with a port 38 to permit the free escape of air from below the plunger. With the parts thus arranged, when the pressure in the diaphragm chamber falls below a predetermined point, the diaphragm is raised by means of the control spring 28, thus opening the valves. These valves are, as stated, slightly unbalanced so that there is a tendency for them to open. As soon as the pressure in the diaphragm chamber reaches the predetermined point, the diaphragm actuates the lever 32 to close the valves.

If desired, a weight may be added to the lever 32 as indicated by dotted lines, to assist in opening the valves. The mechanism may be adapted for a vacuum control in which event the parts are reversed, the regulating diaphragm or regulating chamber being mounted on the bracket 22 or other side of the body and the connection being reversed.

The parts of my improved regulating mechanism are such that they can be readily assembled or disassembled for the purposes of repair. The valve cage may be removed without removing the body 1 from the line or system.

I have illustrated the body 1 as provided with a removable head at each end. In large structures, I contemplate making one head integral with the body. The feature of having both heads removable, however, is of advantage in that the valve cage and valves can be removed from either end of the body as may be convenient.

I have illustrated and described my improvements in a simple and effective embodiment. I have not attempted to illustrate or describe various modifications which I contemplate as I believe the disclosure made will enable those skilled in the art to which this invention relates to adapt

the same as conditions may require. I desire, however, to be understood as claiming my improvements specifically in the form illustrated as well as broadly within the scope of the appended claims.

Having thus described my invention, what I claim as new and desire to secure by Letters Patent is:

1. In a fluid regulator, the combination with the valve casing having a cylindrical bore open at each end, said casing being provided with lateral openings for inlet and discharge; removable heads for said casing; a removable cylindrical valve cage provided with a pair of spaced valve seat holders with valve seats therein, said cage having ports opening between said valve seats, there being an annular passage surrounding said valve cage and communicating with said cage ports and with one of said casing openings, said casing being provided with a longitudinal passage communicating with the other casing opening, said casing heads being provided with passages opening into the ends of the valve cage and communicating with said longitudinal passage; a pair of disk valves provided with wings having sliding engagement with said valve seat holders; a valve stem having a central enlargement upon which said valves are threaded, there being a spacing sleeve between said valves; lock nuts for said valves, the ends of the stem being extended through the casing heads and provided with suitable packing glands; and a pressure actuated member having operative connection to said valve stem.

2. In a fluid regulator, the combination with the valve casing having a cylindrical bore open at each end, said casing being provided with lateral openings for inlet and discharge; removable heads for said casing; a removable cylindrical valve cage provided with spaced valve seats, said cage having ports opening between said valve seats, there being an annular passage surrounding said valve cage and communicating with said cage ports and with one of said casing openings, said casing being provided with a longitudinal passage communicating with the other casing opening, said casing heads being provided with passages opening into the ends of the valve cage and communicating with said longitudinal passage; a pair of disk valves; a valve stem; and a pressure actuated member having operative connection to said valve stem.

3. The combination with the valve casing open at each end, said casing being provided with lateral openings for inlet and discharge; heads for said casing; a valve cage provided with spaced valve seats, said cage having ports opening between said valve seats, there being an annular passage surrounding said valve cage and communicat-

ing with said cage ports and with one of said casing openings, said casing being provided with a longitudinal passage communicating with the other casing opening, said 5 casing heads being provided with passages opening into the ends of the valve cage and communicating with said longitudinal passage; a pair of valves provided with wings having sliding engagement with said valve 10 seat holders; and a stem for said valves.

4. The combination with the valve casing open at each end, said casing being provided with lateral openings for inlet and discharge; heads for said casing; a valve cage 15 provided with spaced valve seats, said cage having ports opening between said valve seats, there being an annular passage surrounding said valve cage and communicating with both of said cage ports and with one of said casing 20 openings, said casing being provided with a longitudinal passage communicating with the other casing opening and with the ends of the valve cage, and a pair of valves coacting with said valve seat provided with a 25 common stem.

23

5. The combination with the valve casing open at each end, said casing being provided with lateral openings for inlet and discharge; heads for said casing; a valve cage provided with spaced valve seats, said cage having ports opening between said valve seats, there being an annular passage surrounding said valve cage and communicating with both of said cage ports and with one of said casing 30 openings, said casing being provided with a longitudinal passage communicating with the other casing opening and with the ends of the valve cage, and a pair of valves coacting with said valve seat provided with a 35 common stem.

40

municating with said longitudinal passage; 25 a pair of valves; and a stem for said valves.

5. The combination with the valve casing provided with lateral openings for inlet and discharge, a removable valve cage provided with spaced valve seats, said cage having 30 ports opening between said valve seats, there being an annular passage surrounding said valve cage and communicating with both of said cage ports and with one of said casing 35 openings, said casing being provided with a longitudinal passage communicating with the other casing opening and with the ends of the valve cage, and a pair of valves coacting with said valve seat provided with a 40 common stem.

In witness whereof, I have hereunto set my hand and seal in the presence of two witnesses.

JOHN E. OSMER. [L.S.]
